CLOSURE FOR STEEL DRUMS

Evor Williams, Mineral Ridge, and David W. Thomas, Youngstown, Ohio, assignors to The Niles Steel Products Company, Niles, Ohio, a corporation of Ohio

Application December 21, 1933, Serial No. 703,338

8 Claims. (Cl. 220—61)

This invention relates to improvements in closures for steel drums or the like, and has reference particularly to split rings which are manipulated by means attached to the rings for causing them to be expanded or contracted. As herein disclosed, the invention is applied to a split ring the ends of which are drawn together for the purpose of clamping the cover down onto the rim of the container body.

10 One of the objects of the invention is the provision of a ring contracting and expanding means which embodies interfitting relatively rigid elements which maintain the ends of the ring in correct position relative to each other, that is so 15 that they necessarily move toward and away from each other in the same plane and substantially in the same circular path.

Another object of the invention is the disposition of a rack and pinion operating means entirely within the circle of the ring.

20 A further object of the invention is the provision of means for preventing the rack from being withdrawn from its guide.

Other objects and features of novelty will appear as we proceed with the description of that embodiment of the invention which, for the purposes of the present application, we have illustrated in the accompanying drawing, in which

Fig. 1 is a plan view of the ring in closed or clamping position.

30 Fig. 2 is a similar view showing the ring in full lines in partly opened position and in dotted lines in fully opened position.

Fig. 3 is a sectional detail view on a larger scale, the view being taken substantially on the line 3—3 of Fig. 1.

Fig. 4 is a cross sectional view on a larger scale, taken substantially on the line 4—4 of Fig. 1, and showing the closing ring applied to a steel drum and cover.

40 Fig. 5 is a cross sectional detail on a larger scale, illustrating the rack guide attached to one end of the ring, this view being taken substantially on the line 5—5 of Fig. 1.

Fig. 6 is a cross sectional view showing the latch 45 for the operating lever, and corresponding in position to the line 4—4 of Fig. 1.

Figs. 7 and 8 are cross sections similar to those of Figs. 3 and 5, showing a modification, these views being taken substantially on the lines 7—7 50 and 8—8 of Fig. 9, and

Fig. 9 is a fragmentary plan view of the same modification.

In Fig. 4 we have shown a fragment of a steel drum or barrel 10, one end of which is rolled over

to form a bead or rim 11. 12 is a cover which is cupped or dished to some extent in order to extend down into the end of the drum. This cover is provided with a surrounding flange 13 which has a concave under surface, within which 5 is mounted a hollow rubber gasket 14 that serves to seal the joint between the cover and the rim 11 of the drum.

The ring 15 in the present instance is C-shaped in cross section so as to embrace the rim 11 and 10 the cover flange 13. When the cover and gasket are in place upon the drum the ring is expanded as far as possible, so as to increase its inner diameter, and is then put in position upon the drum. The C-shaped cross section of the ring 15 provides upper and lower cam surfaces which engage the under side of the rim 11 and the upper side of the flange 13, and accordingly when the ring is contracted the flange 13 is drawn down toward the rim 11 and the gasket 14 is compressed, 20 producing an effective seal.

The means which we employ for contracting and expanding the ring comprises a rack 16, which is welded or otherwise secured to the upper wall of one end of the ring directly adjacent the split therein. Preferably the rack 16 is composed of two thicknesses of metal 16a and 16b welded together, the upper strip 16a having an outwardly directed extension at one end which is welded to the upper wall of the ring 15. The teeth of the rack are on its inner side, and the rack is preferably concave, the pitch line of its teeth conforming to a circle having its center in the center of the ring. The rack 16 slides within a guide 17 which is welded to the end of the ring opposite that to which the rack 16 is attached. The guide 17 is preferably formed as shown in Fig. 5, that is to say it comprises an upper element 17a and a lower element 17b. The lower element 17b has two parallel portions offset from each other. Between these parallel portions there is a wall 17c which is curved along an arc corresponding substantially with the curvature of the rear side of the rack 16, with which it slidably engages. The upper element 17a of the guide is welded to the outer portion of the element 17b, whereby the guide is provided with upper and lower parallel spaced walls, between which the rack slides.

It is desirable to maintain as much rigidity in the rack and guide as in the ring in order that the ends of the ring may move correctly and be maintained in proper register or in alignment with respect to each other, and the rack and guide are therefore made of material sufficiently

heavy to satisfy this requirement. The maintenance of the two ends of the ring in the same plane and in substantially the same circular path facilitates the closing and sealing of the package.

5 In order to move the rack 16 back and forth within the guide 17 and thereby close and open the ring, we mount a pinion 18 between the walls of the guide 17, that is to say in all cases where the guide comprises two spaced walls, with the 10 teeth of the pinion engaging the teeth of the rack. One mounting arrangement is illustrated in Fig. 3, where a pivot pin 19 is shown anchored in the walls of the guide and surrounded by small bearing rollers 20. The pinion 18 is provided with a 15 central bore which receives these rollers, whereby an anti-friction bearing is provided. A plain bearing may of course be employed if desired.

We prefer to form the teeth of pinion 18 in the end of a flat lever 21, which protrudes from the 20 open side of the guide 17. The swinging of the lever 21 from the closed position of Fig. 1 to the dotted line or fully opened position of Fig. 2 expands the ring to the greatest extent possible. While thus expanded, the ring can be fitted down 25 over the end of the drum or barrel to which the head has been applied, and when the lever is swung from its fully open position, indicated in Fig. 2, to its closed position, indicated in Fig. 1, the ring is closed and the flange on the head of 30 the container is pressed down against the bead of the drum or on the intervening gasket, making a tight closure. The pinion 18 by engaging the teeth of rack 15 holds the rack against the rear wall of the guide 17, and therefore prevents 35 relative inward and outward movement of the ring ends.

The pinion teeth, being formed in the end of the lever, of course do not extend through a complete circle, and this fact prevents the pinion 40 from being rotated in either direction beyond a certain predetermined angular position. In the dotted line position of Fig. 2 the lever adjacent the pinion teeth engages the rack, and prevents the further rotation of the pinion. Hence the 45 rack is held in that position against further movement tending to separate the ring ends. The rack and pinion are therefore always in mesh and ready to be operated.

Suitable provision is made for holding the ring 50 and lever in their closed positions so as to prevent accidental loosening of the cover and the arrangement illustrated and described below has been found to be very effective.

The lever 21 is provided near its outer extremity with a hole 22, preferably elongated. This hole 22 is adapted to register with a hole 23 in an inwardly directed extension 24 welded to the ring. The inner extremity of this extension is provided with a down-turned hook which is adapted to receive one edge of the lever 21, as illustrated particularly in Fig. 4. We provide retractable means for holding the lever in engagement with this hook, and for thereby holding the ring in cover-securing position. This means comprises a stop 55 pin 25 adapted to be projected through a hole in the extension 24. We also provide means for retractably holding the stop pin in lever-engaging position, consisting preferably of a strip of spring steel 26 riveted to the extension at 60 21, to which the upper end of the pin 25 is secured in some suitable manner.

When the lever 21 is swung to ring-closing position, it is drawn beneath the hooked end of the extension 24, and its upper surface engages 75 pin 25, pushing the latter up into the position

shown in Fig. 6, when the lever can be moved backward a trifle into the hook as shown in Fig. 4, when the stop pin 25 snaps into the position shown in Fig. 4. The ring cannot then be loosened accidentally. When it is desired to open the drum upon which the ring is used, it is necessary for the operator to first place a finger under the protruding end of the spring 26 and lift it to the position of Fig. 6, when the lever may be manipulated to clear the hook on the extension 10 24. A hole 23' is formed in the spring 26 in register with the hole 23 in the extension 24. In the event that it is desired to provide a positive lock for the lever 21, a padlock or other suitable fastening may be caused to project through the 15 registering holes 22, 23 and 23'.

In Figs. 7, 8 and 9 we have illustrated a modification wherein the mountings of the rack and pinion and the guide for the rack are made particularly secure. In these figures the guide element 30, corresponding to the element 17 of the first described form of the invention, comprises a piece of sheet metal 30a, the outer portion of which is curved to embrace the ring 15, as indicated in Fig. 8. The lower part 30b of the guide element is welded or otherwise secured to the part 30a and throughout the greater part of its extent is spaced away from the inwardly projecting portion of the part 30a so as to form with that part upper and lower guide walls between which the pinion 31 is mounted and between which the rack 32 slides. The guide element 30 is then welded or otherwise firmly attached to the ring 15. The rack element 32 may be formed from a single thickness heavy gauge sheet metal. The rack itself is approximately the same as the rack 16, but the outwardly extending portion at the butt end of the rack is curved so as to embrace the ring 15, as indicated in Fig. 7, and is welded or otherwise joined thereto. The attachment of the elements 30 and 32 to the ends of the ring is of course greatly strengthened by the curved outer portions embracing the ring.

The method of operation of this form of the invention is precisely the same as is that of the first described form, but it will be observed that substantially all of the inwardly projecting elements are positioned at the level of the upper wall of the ring or above that level. Consequently 50 there is nothing to interfere in any way with the lowering of the ring into position upon the barrel or drum when the latter is being closed.

Variations from the described structure may be employed. Accordingly, we desire it to be understood that the scope of the invention is to be regarded as defined exclusively by the appended claims rather than by the foregoing description or accompanying illustration.

Having thus described our invention, we claim:

1. A closing means for steel drums or the like, comprising a cover, a split ring, means for forcing the ends of the ring into cover-securing position comprising a lever pivotally supported upon the ring, the free end of the lever being movable into position adjacent the ring in order to bring the ring into cover-securing position, and means for securing the lever in the latter position comprising a hook mounted upon the ring and adapted to receive the lever, a stop adapted to engage the side of the lever remote from the hook, and spring means for holding the stop retractably in lever-engaging position.

2. A closing means for steel drums or the like, comprising a cover-securing split ring C-shaped

in cross section, a rack carried by one end of the ring, a guide carried by the other end of the ring, a pinion rotatably mounted upon the guide engaging the teeth of the rack, and means for rotating said pinion, said rack and guide being adapted to slide relative to each other in the opening and closing movements of the ring, and having interengaging guide surfaces for holding the ends of the ring in proper relation to each other during their relative movement.

3. A closing means for steel drums or the like, comprising a split cover-securing ring, a curved rack concentric with the ring carried by one end of the ring, said rack being oblong in cross section with its teeth in one edge thereof, a guide carried by the other end of the ring, said guide comprising a back and spaced sides and being adapted to engage the opposite sides of the rack and the edge thereof opposite the toothed edge, a pinion rotatably mounted between the walls of the guide and engaging the teeth of the rack, and means for holding the ring in cover-securing position.

4. In a steel drum of the type in which there is an outwardly extending rim and a head overlapping the rim with a gasket interposed between them, means for closing and sealing the drum comprising a contractible split ring C-shaped in cross section with its ends in end to end relation, a curved rack concentric with the ring rigidly attached to and extending beyond one end of the ring, a pinion carried by the other end of the ring and mounted to turn upon an axis fixed with respect to said end, said pinion engaging and guiding said rack, and means for turning said pinion to draw the ends of the ring toward each other.

5. In a steel drum of the type in which there is an outwardly extending rim and a head overlapping the rim with a gasket interposed between them, means for closing and sealing the drum comprising a contractible split ring C-shaped in cross section with its ends in end to end relation, a curved rack concentric with the ring rigidly attached to and extending beyond one end of the ring, a guide fixed to the other end of the ring in position to receive said rack

and guide it along a circle concentric with the ring, said guide comprising a pinion meshing with said rack, and means for turning the pinion.

6. In a steel drum of the type in which there is an outwardly extending rim and a head overlapping the rim with a gasket interposed between them, means for closing and sealing the drum comprising a contractible split ring with its ends in end to end relation, a curved rack concentric with the ring rigidly attached to and extending beyond one end of the ring, a pinion carried by the other end of the ring and mounted to turn upon an axis fixed with respect to said end, said pinion engaging said rack, said rack and pinion being spaced radially of the ring, and means for turning said pinion.

7. In a steel drum of the type in which there is an outwardly extending rim and a head overlapping the rim with a gasket interposed between them, means for closing and sealing the drum comprising a contractible split ring with its ends in end to end relation, a curved rack concentric with the ring rigidly attached to and extending beyond one end of the ring, a pinion carried by the other end of the ring and mounted to turn upon an axis fixed with respect to said end, said pinion engaging said rack, said rack and pinion being arranged upon the inner side of the ring, and means for turning said pinion.

8. In a steel drum of the type in which there is an outwardly extending rim and a head overlapping the rim with a gasket interposed between them, means for closing and sealing the drum comprising a contractible split ring C-shaped in cross section with its ends in end to end relation, a curved rack concentric with the ring rigidly attached to and extending beyond one end of the ring, a guide for the rack fixed to the other end of the ring and having spaced walls, a pinion mounted in said guide between said walls and held thereby in mesh with said rack, thus maintaining the end of the ring in end to end relation along a contracting circle as the ring is closed, and means for rotating said pinion.

EVOR WILLIAMS.
